UNITED STATES PATENT OFFICE.

MARTIN KAUTH, OF BUFFALO, NEW YORK.

SUSPENDING AND DETACHING DEVICE.

SPECIFICATION forming part of Letters Patent No. 333,757, dated January 5, 1886.

Application filed November 30, 1885. Serial No. 184,376. (No model.)

To all whom it may concern:

Be it known that I, MARTIN KAUTH, a citizen of the United States, residing at Buffalo, in the county of Erie and State of New York, have invented certain new and useful Improvements in Suspending and Detaching Devices; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates particularly to that class of suspending and detaching devices which are employed in hanging pictures or removing them from the walls, or for other analogous uses; and it consists in a certain improved construction, which will be more fully hereinafter described and claimed.

20 In the drawings, Figure 1 is an elevation of the longer side of my improved device. Fig. 2 is an elevation of the shorter side of my improved device. Fig. 3 is a side elevation of a modified form. Fig. 4 shows my device provided with an auxiliary attachment. Fig. 5 is a horizontal section taken in the line $\alpha\alpha$ of Fig. 3, and Fig. 6 is a perspective view of Fig. 1.

30 Referring to the drawings, a is the base, of hollow cylindrical form, adapted for the reception of the end of a pole or staff, b . From this base a extends upwardly and outwardly four prongs, c , c' , c'' , and c''' , and the tops of these prongs are each provided with a fork, c^4 . Between the forked prongs c^4 and c^4 are the wide tapering spaces d d . Between the prongs c and c'' and prongs c' and c''' are the narrower tapering spaces d d .

40 The operation of the device just described is as follows: The pole or staff b is grasped in the hand, and any pair of the four prongs are passed up into the angle of the wire or cord by which the picture is suspended until the forked ends engage therewith, the nail or hook resting in the spaces d d or d d '. In this manner the wire or cord can be readily disengaged and the picture removed from the nail or hook.

45 50 I am aware that a single pair of prongs with forked ends is old; but with my improved construction I obtain a device capable of much

more extended and varied uses than the old form, as with my arrangement I have two sets of forked prongs, the ends of which are at 55 different distances apart, thus adapting them for different angles in the suspending picture wire or cords, the angles varying as they do for different widths of pictures. Then, too, the space d d and d d ' between the sets of 60 prongs are of different widths, both being much larger in width than the forks c^4 , which adapts my device for use in stores where various articles are suspended from the ceiling by ropes or cords too large in diameter to fit within the 65 forks c^4 of the prongs. The forked ends of the prongs may be covered with leather or other suitable material to prevent injury to the walls or ceiling with which my device comes in contact, as shown in Fig. 4.

70 Where it becomes necessary to hold the pole or staff at an angle to remove a picture from the wall, or in case you do not wish to remove any furniture which may be below the picture, the construction shown in Figs. 1 and 2 would 75 not effect the purpose. To provide for this contingency, I have arranged the forked ends of the prongs in an inclined plane, as clearly shown in Fig. 3, which enables the device to be properly presented into the angle of the 80 wall for the purpose desired.

75 When my improved device is to be employed in stores, where objects are to be hung or removed from the ceilings, and where a long reach is required, I have provided the 85 construction shown in Figs. 4 and 5, in which the base a is provided on its side with the triangular socket e . (More clearly shown in Fig. 5.) Into this socket is removably placed the elongated arm f , at the outer end of which 90 is secured in an upright position a set of forked prongs similar to those at the end of the pole or staff b . By this means suspended articles are within easy reach from all points, and can be readily hung or removed from the ceiling. 95

As hereinbefore stated, I am aware that a single pair of prongs with forked ends is old, and I do not therefore claim such construction; but

What I do claim is—

100 1. A suspending and detaching device consisting of the two sets of prongs c , c' , c'' , and c''' , each provided at its end with the fork c^4 , and having the spaces d d and d d ' between

the prongs, the whole mounted upon a pole or staff, substantially as shown and described.

2. A suspending and detaching device having its two sets of forked prongs $c\ c'$ and $c^2\ c^3$ arranged in an inclined plane, substantially as and for the purpose stated.

3. A suspending and detaching device consisting of the two sets of prongs $c\ c'$ and $c^2\ c^3$, each provided at its end with the fork c^4 , and to the arm f , secured to the base a , and having at its outer end an auxiliary set of prongs, substantially as and for the purpose stated.

4. A suspending and detaching device consisting of the arm f , secured at or near the upper end of a pole or staff, and provided at its

outer end with two sets of forked prongs, substantially as and for the purpose stated.

5. A suspending and detaching device consisting of the two sets of forked prongs $c\ c'$ and $c^2\ c^3$, such prongs being covered with leather or other suitable material, substantially as and for the purpose stated.

In testimony whereof I have signed my name to this specification in the presence of two subscribing witnesses.

MARTIN KAUTH.
